UNITED STATES PATENT OFFICE

168,321

DRESS

Mary Shipmon, Pittsburgh, Pa.

Application May 14, 1951, Serial No. 15,163

Term of patent 3½ years

(Cl. D3—26)

To all whom it may concern:

Be it known that I, Mary Shipmon, a citizen of the United States, residing at 720 Herron Avenue, city of Pittsburgh, State of Pennsylvania, have invented a new, original, and ornamental Design for a Dress, of which the following is a specification, reference being had to the accompanying drawing, forming a part thereof.

Fig. 1 is a front view of a dress showing my new design;

Fig. 2 is a rear view of the dress shown in Fig. 1; and

Fig. 3 is a side view of the dress shown in Fig. 1.

I claim:

The ornamental design for a dress, as shown.

MARY SHIPMON.
